(57) **CLAIM**

The ornamental design for a scanner as shown and described.

DESCRIPTION

FIG. 1 is a top front perspective view of a scanner showing a first embodiment of the claimed design;

FIG. 2 is a front side elevation view thereof;

FIG. 3 is a rear elevation view thereof;

FIG. 4 is a right side elevation view thereof;

FIG. 5 is a left side view thereof;

FIG. 6 is a top plan view thereof;

FIG. 7 is a bottom plan view thereof;

FIG. 8 is a top front perspective view of a scanner showing a second embodiment thereof;

FIG. 9 is a front side elevation view thereof;

FIG. 10 is a rear elevation view thereof;

FIG. 11 is a right side elevation view thereof;

FIG. 12 is a left side view thereof;

FIG. 13 is a top plan view thereof; and,

FIG. 14 is a bottom plan view thereof.

The broken lines in the figures show portions of the scanner that form no part of the claimed design.

1 Claim, 14 Drawing Sheets
